United States Patent Office

Des. 211,917

Patented Aug. 6, 1968

211,917

DESK TRAY OR SIMILAR ARTICLE

Florence R. Copeland, 2112 Spring House Road,
Broomall, Pa. 19008, and Gloria M. De Luca,
812 Oakwood Drive, Glenolden, Pa. 19036

Filed June 1, 1967, Ser. No. 7,334

Term of patent 14 years

(Cl. D74—9)

FIG. 1

FIG. 2

FIG. 4

FIG. 3

We claim:

The ornamental design for a desk tray or similar article, substantially as shown.
